UNITED STATES PATENT OFFICE.

OAKLEY A. GANT, OF OAKMAN, ALABAMA.

WIRE-COILING TOOL.

No. 821,162.

Specification of Letters Patent.

Patented May 22, 1906.

Application filed November 23, 1905. Serial No. 288,719.

To all whom it may concern:

Be it known that I, OAKLEY A. GANT, a citizen of the United States, residing at Oakman, in the county of Walker and State of Alabama, have invented new and useful Improvements in Wire-Coiling Tools, of which the following is a specification.

This invention relates to certain improvements in tools for coiling wire, and more particularly relates to a tool for coiling one length or ply of wire around another length or ply of wire.

An object of the invention is to provide a simple and efficient tool of an improved construction for coiling or wrapping one wire length around and connecting the same to another wire length, and particularly adapted to secure insulator tie-wires to line-wires and for connecting line-wires and which can also be used as ordinary pliers or pincers.

The invention consists in certain novel features in construction and in combinations or arrangements of parts, as more fully and particularly set forth hereinafter.

Referring to the accompanying drawings, Figure 1 is a perspective view of the tool, showing the jaws thereof partially separated. Fig. 2 is a perspective view showing the tool from a different angle. Fig. 3 is a cross-sectional view through the two jaws in closed position. Fig. 4 is a detail view of the wire-clipper.

The tool consists of two crossed pivoted levers pivotally joined by the transverse pivot-pin 1 and having their ends extended to form the handle 2, while the opposite ends of the levers form the two corresponding approximately similar jaws 3, capable of coacting in performing the ordinary functions of pliers or pincers.

The inner face of each jaw 3 is formed with a transverse semicylindrical socket, groove, or depression 4, opening through one side edge of the jaw and extending the greater portion of the distance through the jaw and at its inner end terminating in the transverse semicylindrical contracted line-wire-receiving groove 5, extending the remainder of the distance through the jaw and opening through the opposite side edge of the jaw. The grooves of the two jaws are arranged in juxtaposition and register or coincide when the jaws are closed together to form the enlarged cylindrical opening or socket 4, terminating in the contracted passage or opening 5. Each jaw is formed with a perforation 6, ex-

tending completely therethrough at right angles to the longitudinal axis of the grooves 4 5 and to the length of each jaw. Each perforation 6 at its inner end opens through the floor of the enlarged groove 4 at a point about midway the length of said groove and at its outer end opens through the flat outer face of the jaw. The perforations 6 through one jaw is preferably of a larger size or diameter than the perforation 6 of the other jaw. The grooves and perforations are arranged intermediate the length of the jaws, whereby the solid outer portions 7 of the jaws beyond said grooves and perforations can be formed with the flat or plain inner surfaces to coöperate in performing the various functions of ordinary pincers or pliers. The two levers are notched at 8, just in rear of the pivot-pin, to form the coöperating shearing cutting edges 9 for cutting wire. One or both of these edges 9 are inclined, so that as the edges are brought together the rear or free ends of the edges will first meet, thereby confining the wire in the notches during the cutting action and causing the blades to draw across the same at an angle.

The implement described is particularly intended for use in applying or repairing telegraph or telephone lines, in applying the insulator tie-wires, and in coupling or connecting line-wires. In using the implement to apply the wires the tie-wire is passed around the insulator and a free end thereof passed outwardly through one of the perforations 6 of the coiling-tool described. The jaws of the tool are then closed on the line-wire with the same passing through passage 4 5 and with end 4 of the passage next to the insulator. The tool is then rotated around the line-wire, thereby coiling the tie-wire tightly to and around the line-wire, the tie-wire feeding in through the perforation 6. The coil around the line-wire is formed in the enlarged portion 4 of the tool, and the small size of the perforation 6 causes the proper feeding of the tie-wire and the proper tension thereon. When the end of the tie-wire has been completely guided and fed in through perforation 6 and the coil is completed, the jaws are separated and the tool removed. The tool is then reversed, and the other end of the tie-wire is then passed outwardly through one of the perforations 6, and the jaws are closed on the line-wire at the opposite side of the insulator with the enlarged portion 4 of the wire-passage next to the insulator. The tool is then

rotated around the line-wire, gradually sliding thereon away from the insulator to form the final coil of the tie-wire on the line-wire and to complete the operation of fastening the line-wire to the insulator by means of the tie-wire.

The tool is equally well adapted to connect or couple together line or other wires. The ends of the two wires to be coupled together are bent laterally and hooked together, and one of the lateral ends is passed outwardly through the larger of the two perforations 6, and the jaws are then closed together with the line-wire of the end passed through the 15 perforation extending loosely through passage 4 5. The tool is then rotated around said line-wire to coil said end thereon. The operation is then repeated to coil the other lateral end on its line-wire, the tool being 20 held in the reversed position.

What I claim as new, and desire to secure by Letters Patent, is—

1. A wire-coiling tool comprising the two crossed pivoted levers having a pair of coöperating pincer-jaws, formed at their inner 25

faces with registering similar transverse coil-receiving grooves terminating in reduced line-wire-receiving grooves, a jaw having a wire feeding and guiding perforation extending therethrough and opening into the floor of the coil-receiving groove, substantially as described. 30

2. A pair of pincers consisting of pivotally-united levers having at the end approximately similar coöperating jaws at their inner faces having the transverse registering grooves extending completely across the same, and the perforations extending through the jaws at right angles to the length thereof and to the axis of the passage formed by said 35 grooves and opening into said passage intermediate the length thereof, one perforation being of greater diameter than the other, substantially as described. 40

In testimony whereof I affix my signature 45 in presence of two subscribing witnesses.
